VIBRATOR AND METHOD OF TREATING
CONCRETEWalter H. Horsch, Wheaton, Ill., assignor to
Massey Concrete Products Corporation, Chi-
cago, Ill., a corporation of Virginia

Application October 29, 1931, Serial No. 571,812

4 Claims. (Cl. 74—61)

The present invention relates to vibrators and methods of treating concrete, and is particularly concerned with apparatus and methods for high frequency vibration of concrete. The vibrators themselves are, however, capable of general application and may be used in many different industries for producing mechanical vibrations, and I do not wish to be limited to the particular use described.

10 Vibrators employing an eccentric weight on the shaft of a rotating motor armature, have been employed for mechanical vibration of concrete, and ordinary motors have been equipped with a small eccentric weight for the purpose of inducing some sort of movement due to the inertia and eccentricity of the weight. Ordinary motors are not provided with bearings adapted to withstand the strain which is put upon them when an eccentric weight is added to the shaft, and 15 the use of the eccentric weight in the devices of the prior art has placed such a strain on the bearings that the life of the motor is very short. Furthermore, the single eccentric weight utilized on the motors of the prior art does not give vibrations in any predetermined direction, and it is 20 very difficult to control the vibrations or movement induced by a motor having a single eccentric weight.

When a motor shaft is provided with a single eccentric weight at one end, and the shaft is rotated, the eccentric weight would be moved in a circle by the motor shaft were it not for the fact that the eccentric weight possesses inertia, and being subjected to a constant acceleration to 25 maintain a circular path, the movement of the eccentric weight depends upon the amount of its mass relative to the mass of the motor and other parts connected to the motor.

When a particle revolves in a circle, it has an 30 acceleration toward the center which is equal to the square of the velocity divided by the radius, and to cause this acceleration, there must be a force directed toward the center, and this centrifugal force may be determined according to 35 the following equation:

$$F = m \frac{v^2}{r}$$

where "m" represents the mass. Against this 40 force the particle will exert an equal and opposite reaction on the body that exerts the force toward the center, that is, on that part of the weight which attaches the mass to the shaft, and through the shaft on the motor, and everything which is 45 secured to it. Thus, the motor and its associated

masses are endeavoring to move the eccentric weight and the eccentric weight is reacting against the motor mass to move the motor. The result is that the eccentric weight moves in a smaller circular orbit than it would take if the motor could be assumed to be absolutely fixed, and the motor itself is oscillated in a relatively small circular orbit, the oscillation of the motor being opposite in direction to that of the eccentric weight.

The sizes of these orbits depend upon the relative masses of the motor and eccentric weight and the square of the velocity of both masses. This can readily be demonstrated by referring to the following equations in which the sub-indicia M is used for the motor, and the sub-indicia W for the eccentric weight. The centripetal force exerted on the eccentric weight by the motor to cause an acceleration toward the center and keep the eccentric weight moving, may be expressed by the equation,

$$F_m = m_m \frac{v_m^2}{r_m}$$

The centrifugal force exerted by the reaction of the eccentric weight on the shaft may be expressed by the following equation:

$$F_w = m_w \frac{v_w^2}{r_w}$$

These forces must be equal and opposite, and it will thus be found that the relation of the masses velocities and radii of any particles subjected to these forces may be determined by the following equations:

$$F_m = F_w = m_m \frac{v_m^2}{r_m} = m_w \frac{v_w^2}{r_w}$$

$$\frac{m_m}{m_w} = \frac{v_w^2 r_m}{v_m^2 r_w} \quad \frac{v_w}{v_m} = \sqrt{\frac{m_m r_w}{m_w r_m}}$$

It will thus be observed that contrary to the usual supposition, an ordinary eccentric weight on the motor shaft does not cause reciprocatory vibrations of the motor, but actually causes rotation of the motor in an orbit, and this orbit is smaller in size than the orbit of the eccentric weight depending on the square of the velocities and the masses of the respective particles.

It is found that if the ordinary motors of the prior art which are provided with small eccentric weights are fixedly secured to relatively stiff forms, such as cylindrical pipe forms, practically no vibratory effect is produced, because the weight of the concrete and pipe is added to the

mass of the motor and the eccentric weight is so small that it produces no appreciable movement of the pipe and concrete.

When such an ordinary motor with a small eccentric weight is resiliently mounted on a concrete form or other body, sufficient movement of the motor itself is permitted so that the motor body may act as a hammer in hammering against the form, and thereby vibrating the form, or the motor may react against the form through its resilient support, to produce some vibration in the form and concrete, but it will be evident that the ordinary motors of the prior art were definitely limited in the power of vibrations which could be applied by reason of the definite limitation in the size of eccentric weights which could be applied to the motor shaft, and the movement of the ordinary eccentric weight motors of the prior art could not be definitely controlled in direction for the reason that the motor tended to wobble in an orbit.

This wobbling motion is further accentuated by the fact that the eccentric weight was only placed on one end of the shaft, and the weight was not only eccentrically located with respect to the center of the shaft, but eccentrically located with respect to the center of mass of the motor.

Thus, the devices of the prior art tended to produce rotary oscillations rather than reciprocatory vibrations, and any reciprocatory vibrations that were secured were the result of the greater freedom of movement of the form or motor body in some particular direction.

One of the objects of the present invention is the provision of an improved motor vibrator which is adapted to produce reciprocatory vibrations in a predetermined direction rather than rotary oscillations of the type produced by the devices of the prior art.

Another object is the provision of an improved vibrator which is adapted to give longer and more efficient service by virtue of the fact that the motor bearings are not subjected to the constant wobbling motion of the motor and shaft which is present in the devices of the prior art, and also the provision of improved structures in which the vibrator itself may be provided with special bearings for withstanding any vibration to which they are subjected.

Another object is the provision of an improved vibrator which is adapted to permit the use of more power in the vibration of concrete or other articles, and which is adapted to exert greater force on the articles to be vibrated.

Another object is the provision of an improved vibrator, the effect of which may be controlled more readily, and the provision of improved vibrating apparatus by means of which the vibration of a multiplicity of different vibrators may be synchronized and maintained in the proper direction, so that the different vibrators augment each other's effect rather than work against each other.

Another object is the provision of an improved method of manufacturing and treating concrete by means of which concrete of better characteristics may be made.

Other objects and advantages of the invention will be apparent from the following description, and from the accompanying drawings, in which similar characters of reference indicate similar parts throughout the several views.

Referring to the drawings, of which there are four sheets;

Fig. 1 is an elevational view in partial section, showing one form of vibrator constructed accord-

ing to the present invention in connection with a supporting truck and a concrete form carried by the truck;

Fig. 2 is an elevational view in partial section, showing the construction of the vibrating unit, 5 of Fig. 1;

Fig. 3 is a transverse, sectional view taken on the plane of the line 3—3 of Fig. 2, showing the drive for the vibrating unit of Fig. 2;

Fig. 4 is an elevational view in partial section 10 of another vibrator employing a direct drive;

Fig. 5 is a top plan view of the vibrator of Fig. 4, with the concrete form in section;

Fig. 6 is an elevational or plan view of a multiple vibrator installation. This figure represents an 15 elevational view when the vibrators are applied to the bottom of the form for the purpose of effecting vertical vibration or a plan view when the vibrators are applied to the side of the form;

Fig. 7 is an elevational view in partial section, 20 showing another vibrator adapted to produce controlled vibrations in a predetermined direction;

Fig. 8 is a sectional view of Fig. 7, taken on the plane of the line 8—8;

Fig. 9 is a sectional view similar to Fig. 8, of a 25 modified form of gearing or drive for producing a higher rate of vibration.

Referring to Fig. 1, this is an installation including a vibrator which may be used with any type of ordinary motor, for the reason that the 30 motor itself is not subjected to the vibration and its bearings are not subjected to any strains for which they were not designed. Thus, the installation of Fig. 1 includes an ordinary motor 20, a flexible shaft 21, and a vibrating unit 22 35 which may be fixedly secured to the truck 23. The truck 23 supports one or more concrete forms 24 which are to be subjected to high frequency vibration in order to improve the characteristics of the concrete located in the forms 40 24, and the particular characteristics of the concrete and mixtures will be described in detail hereinafter.

The truck 23 may consist of a sheet metal truck having a platform 25 with a handle 26 45 and a plurality of wheel supports 27 secured to the platform 25 by riveting or spot welding at 28 and by braces 29. The wheel supports 27 may be provided with bores forming bearings for the wheel shafts 30, but the shafts 30 are preferably journaled in a movable bearing block 31 50 of substantially H-shape in cross section, which is slidably mounted in a slot 32 and urged downward by a compression spring 33. The bearing block 31 is retained in its slot by a plate 34 suitably secured by screw bolts on the wheel supports 27.

Where the wheels are secured to the truck without springs, vibration may nevertheless be effected, but the weight of the wheels is added 60 to the weight of the truck, whereas the spring mounted wheels permit the vibration of the truck platform 25 and concrete forms without necessity for vibration of the wheels, and this effects a reduction in the noise of the operation 65 since the wheel need not vibrate relative to the track 35 and the form is resiliently supported on the spring 33 for vibration in a vertical direction.

The vibrating unit 22 may consist of a casing 70 36 of cast metal provided with attaching flanges 37 which may be secured directly to the platform 25 by a plurality of screw bolts 38.

Referring to Fig. 2, the casing 36 may consist of a metal casting having substantially rectan- 75

5 gular walls and provided with an open side 38 which is covered by a cover plate 40. The cover plate may be secured to casing 36 by screw bolts 41 passing through the cover plate and threaded into the wall of the casting.

10 The casing 36 is also provided with transverse circular bores 42, 43 aligned with each other and adapted to receive the bearings 44, 45 for the vibrator shaft 46. Bearing 45 may be secured in 15 casing 36 by screw bolts 47 while the opposite bearing 44 may be secured in place by the end fitting 48 of the flexible shaft 21 which is provided with casing 49.

15 The bearings 44, 45 may be made of special bearing metal and of any suitable size, weight and characteristics for withstanding the vibration to which the vibrator 22 is subjected, whereas the motor 20 which is connected to the vibrator by flexible shaft 21, is not subjected to 20 any unusual strains.

25 The shaft 46 is fixedly secured to a rotating gear or wheel 50 by means of a key 51 in slot 52 and the shaft 46 is preferably provided with thrust bearings 53 on each side of the gear 50. The gear 50 may comprise a cast metal member which is formed with a hub 54, a web 55, and a rim 56 having teeth 57. One sector of the 30 circular web 55 is preferably made thicker than the web 55, being substantially as thick as the length of the hub 54, forming an eccentric weight 58 on the gear 50.

35 The vibrator 22 is also provided with bearings similar to those described and shown in Fig. 3, for the shaft 59 which is fixedly secured in the same way to a second gear or rotating member 60 having an eccentric weight 61. All of the other details of shaft 59 and rotating member 60 may be exactly as described with respect to the 40 details of Fig. 3, except that rotating member 60 is driven through the engagement of its teeth 57 with the teeth 57 of the gear 50, and therefore it need not be provided with a flexible shaft 21.

45 The teeth 57 of the gears 50 and 60 are so meshed with respect to the eccentric weights 58, 61, that both weights are at the same side as shown in Fig. 2 when the weights are in that position, and when the gears rotate to the opposite position both weights are at the opposite side of the vibrator. When the gear 50 is 50 rotated in a clockwise direction 90°, it will be observed that both weights are adjacent each other between the shafts 46, 59 and when gear 50 has been rotated three-fourths of a revolution 55 in a clockwise direction, both eccentric weights 58, 61 will be located at the opposite ends of the vibrator casing 36.

60 The casing may also be provided with laterally and rearwardly or downwardly projecting hooks 62 at each side for use in attaching the casing to articles to be vibrated by means of cables or other securing devices. When the vibrator is to be attached to a flat surface, the engaging surface 63 may be substantially plane, but when it 65 is to be attached to a curved form, it may be curved complementarily to the form, such as a pipe form, or provided with an extra fitting to adapt it to the form, or with a pair of angularly disposed surfaces 64, 65, as shown in Fig. 5, for 70 engaging circular forms of different size.

75 The mode of operation of the vibrator of Figs. 1 to 3 is as follows:

When the motor 20 is driven at an appropriate speed, such as, for instance, 3600 R. P. M., the gear 50 is rotated by means of flexible shaft 21

and gear 60 is rotated in unison with the gear 50. When the eccentric weights 58, 61 are rotating, and weight 58 is moving in the direction of the arrow 68, the weight 61 is moving in the direction of the arrow 67. The weights 58 and 61 are preferably equal in mass and consequently the force which would be exerted on the vibrator by weight 58 is counter-balanced by the force of weight 61 during this period of the rotation. It will be found that a similar situation exists when weights 61 and 58 are moving in the direction of the arrows 68, 69 at the bottom of Fig. 2. The forces exerted on the vibrator by these eccentric weights are at all times equal and opposite to each other in a horizontal direction in Fig. 2, and consequently there is no tendency to vibrate in the horizontal direction in Fig. 2.

When the weight 58 is moving upward in the direction of arrow 70, weight 61 is moving upward in the direction of the arrow 71, and the reaction causes an equal and opposite downward force indicated by the arrow 72 on the vibrator 22. When the eccentric weights are moving downward in the direction of the arrows 73 and 74, an equal and opposite upward reaction is produced on the vibrator 22 in the direction of the arrow 75.

It will thus be observed that the present vibrator is adapted to effect vibrations in a predetermined direction, and the tendency to cause rotary oscillation or motion in any other direction is balanced out by the equal and opposite eccentric weights rotating in opposite directions.

30 In the present embodiment, the vibrator has 35 been connected to the truck in such manner as to produce vertical vibrations for the purpose of causing the concrete mixture to settle into every portion of the form and to improve the characteristics of the concrete by the elimination of 40 air and excess water, and by bringing the portions of the aggregate into closer engagement with each other, but the present vibrator may be utilized for inducing horizontal vibrations or 45 vibrations in any predetermined direction, depending upon the mode of its connection to the form, concrete or vibrating members embedded in the concrete.

50 It will thus be observed that the direction of the vibrations may be controlled and their amplitude may be controlled since it is possible to use eccentric weights disposed at a greater radius. The force of the vibrations may be controlled since it is possible to use larger masses for eccentric weights in a vibrating unit particularly 55 adapted to withstand such strains, and the speed of vibrations may be controlled by the interpolation of a speed reduction or speed increasing gearing or a variable transmission 76 with or without a clutch 77.

60 Referring to Figs. 4 and 5, this is a modification comprising a vibrator unit 78 which is provided with a fitting 79 having the angularly disposed surfaces 84, 85 for engaging the outside 65 of a metallic pipe form 80. The vibrator may be secured on the pipe form by a plurality of cables 81 passing about the pipe form 80 and having turnbuckles 82 engaging the hooks 62. It should be understood, however, that any of the forms or modes of securing the vibrator to 70 the form may be employed, which are shown in my co-pending application, Case 2, Serial Number 593,585, filed February 17, 1932, disclosing electromagnetic securing devices which may be attached to the concrete form by merely turn- 75

ing on the switch when the vibrator is in close juxtaposition to the form, thereby eliminating much of the labor in securing the vibrator to the form, and effecting a great saving of time when 5 a large number of different forms are vibrated.

The vibrating unit 78 is provided with a base plate 83 having an upwardly projecting wall 84 which joins two casings 85, 86, similar in form to the casing 32 of the vibrating unit 22 10 previously described. The casing 85 comprises a pair of walls 87, 88 forming a gear chamber 89 for receiving the gears 90, 91 which are provided with eccentric weights 88, 91, similar to the weights of Fig. 2.

15 In this embodiment, the gears are fixedly secured to the shafts 92, 93 by set screws 94 and anti-friction roller bearings 95 have been provided with races 96, 97, cover plates 98, and oil seals 99. The motor 100 may have its base 101 bolted or otherwise secured to the base 83 and the motor 100 preferably has its shaft 102 substantially aligned with the shafts 93, 103 in the opposite vibrating units 85, 86. The shaft 103 bears a similar eccentric weight gear 104 and a 25 shaft 105 bears a similar eccentric weight gear 106. The relation of the eccentric weight gears 104, 106 to each other is similar to the gears 58, 60, previously described, and the weights are also so located that they bear a definite relation 30 with respect to the weights on the gears 90, 91 at the other side of the vibrator, so that the eccentric weight on gear 106 rotates in the same direction as the eccentric weight on gear 90 at the same time, and the eccentric weight on gear 35 104 rotates in the same direction as the eccentric weight on gear 91 at the same time.

The motor shaft 102 is preferably connected to the gear shafts 93, 103 at each end through a universal joint 107 to eliminate the absolute necessity 40 for perfect alignment between the motor shaft and the gear shafts. The universal joint 107 may consist of a pair of plates 108, 109 having apertures for receiving laterally projecting lugs 110 on a fabricoid disc 111.

45 The operation of this vibrator is substantially as follows: When the eccentric weights are moving in a vertical direction in Fig. 4, the forces induced are counter-balanced, but when they are moving in a horizontal direction, the forces induced by the eccentric weights are additive and direct mechanical vibrations are produced in a horizontal plane. The provision of a separate vibrating unit 85, 86 on each side of the motor, produces a balanced condition with respect to 50 the motor, and there is less tendency for wobbling of the motor shaft in a horizontal plane than would be the case if a single vibrating unit were employed.

The amount of power of the vibrator may be 60 varied by using different weights of different size or eccentricity, the weight being disposed closer to the hub in case vibrations of lesser amplitude are desired, and the size of the motor chamber 112 may be such that motors of different sizes 65 may be employed on the same vibrator unit. The present structure is thus adapted to be used with standard motors of many different sizes to produce vibrators to meet widely varying conditions, without the necessity for modifying the motor 70 structure or the stock of vibrator parts except the eccentric weight gears.

The present vibrator is capable of producing vibrations in any predetermined direction, the vibrations being controlled and balanced with 75 respect to the motor structure, and while the

motor is subjected to vibration with the unit, much wear on the motor may be eliminated. If desired, the motor may be supported on resilient rubber blocks interposed between the motor base and the vibrator base 83 to reduce the vibration 5 on the motor.

The vibrations produced by the vibrator in concrete for the purpose of improving its characteristics, should be controlled in regard to the proper frequency, the proper amplitude, and the 10 proper amount of power. Low frequencies equivalent to the old methods of jiggling or jogging the concrete are incapable of producing the beneficial results desired. If the forcible impulses which are given to the form are too great, it may 15 cause the concrete to separate from the form and also cause it to break apart or crack at certain points, while the concrete is green. Furthermore, movements of too great an amplitude tend to cause the concrete to slosh or move as a body 20 back and forth in the form, separating from the wall of the form.

Consequently, it is not desirable to exert too much power on any predetermined part of the form, and if the form or mass of the concrete 25 cannot be placed in vibration by a single vibrator of reasonable size at one point, it is found desirable to utilize a plurality of vibrators located at regularly spaced points, or such points that the entire mass of concrete is placed in a proper state 30 of vibration.

The vibrations spread in all directions through the concrete from the point of their application, and they diminish in intensity and amplitude as the distance increases from the source of vibrations, this decrease in intensity and amplitude being caused by the dissipation of the energy in the concrete and the frictional resistance which the particles have to movement of any kind. 35

Referring to Fig. 6, this is an elevational view 40 with the form in section, showing a multiplicity of different vibrators adapted to synchronize to produce synchronized vibrations in various parts of the concrete 113, which is supported in form 114. If two vibrators are employed on the same mass of concrete, the vibrators working against each other, such as, for example, when one vibrator tends to push in one direction at the same time that another vibrator tends to push in another direction, the resultant vibration might be 45 exactly zero if it were possible to make the forces of the vibrators exactly equal and opposite. It is a physical impossibility to cause two electric motors of the commutator type or induction type, or any other type except synchronous motors, to 50 rotate together, for the reason that there is a decrease in speed caused by load, and the friction load, even at idling speed, varies in different 55 motors.

Consequently, great difficulty is encountered 60 when more than one vibrator is employed on a concrete form, in getting the vibrators to work together and it is found that much of the power may be wasted because the vibrators of the prior art are not synchronized and do not have their forces acting in the proper direction at the proper time. 65

Referring to Fig. 6, this is an arrangement 70 whereby the eccentric weights of the separate vibrator units 115, 116, 117, etc., are always maintained in the proper relation to each other, so that all vibrate simultaneously and synchronously and in the proper direction to secure the additive effect of all of the vibrators. That is, when the eccentric weights of the unit 115 exert an up- 75

ward impulse on the form 114, the eccentric weights of the units 116, 117 also exert an upward impulse and the same action takes place when the units are exerting a downward impulse on the form. As a result, all the vibrators vibrate together synchronously and the parts of the form adjacent to the vibrators, vibrate synchronously and vibrations are applied to a multiplicity of different parts of the form in the same direction and at the same time, the impulses being synchronized.

For this purpose, the vibrating unit 115 has its shaft 118 connected by a universal joint 119 to a shaft 120 of the unit 116, which in turn is connected by a universal joint 121 to the shaft 122 of the unit 117. When these units are connected together, they are connected with their eccentric weights in the proper position, and all of the units may be driven from the same shaft 118 or a multiplicity of units of the type shown in Fig. 4 may be substituted for the vibrating units 116, 117.

It is thus optional to utilize with the unit 115 a motor large enough to drive a number of different vibrators, or a plurality of different vibrators, each having a motor, may be connected together by shafts and universal joints.

It should be understood that the flexible shaft drive shown in Fig. 1 may be utilized with a multiplicity of units of the type shown in Figs. 1 and 2, and flexible shafts may be employed between different vibrators to keep them in proper synchronized relation to each other, but in general, it will be found better to employ ordinary shafts and gearing for the reason that a flexible shaft permits more torsional movement, and after a period of operation, it may be found that vibrators connected by a flexible shaft will be slightly out of synchronous relation.

The vibrations which are induced in the form 40 by the master vibrator 115, will, however, tend to draw the other vibrators 116, 117 into synchronism, and therefore flexible shafts may be substituted for the shafts 120, 122 when the units are located close enough together on the form to 45 take advantage of this situation.

Another mode of maintaining the units in synchronous operation comprises the marking of weights and the provision of synchronous motors for operation on alternating current with special 50 coils for starting the motors and marking devices for indicating the position of the eccentric weight in the vibrator so that the user may note whether or not the weights are all moving in the same direction at the same time.

55 By shutting off the current and permitting the synchronous motor to skip, or by using some braking device to cause the synchronous motor to skip temporarily, the weights can be brought into synchronism and all the vibrators can be made 60 to work together. For this purpose, the eccentric weight itself may be exposed through a window in the housing.

Another mode is to provide a temporary connection between the synchronous motors during 65 the starting of the separate motors.

It should also be understood that while all the vibrators are shown on the same side of the form in Fig. 6, they might be disposed on opposite sides of the form and timed to vibrate in opposite directions so that their vibrating effect on the concrete would be additive.

Referring to Fig. 7, this is another modified form of vibrator having a casing 123 supported upon a base 124 which may be similar to any of 75 the bases previously described for attachment to

circular or flat concrete forms, and the vibrator casing 123 may be secured to the end of the motor casing 125 by a plurality of screw bolts 126. The vibrator casing 123 is closed by cover plate 127 and rotatably supports a pair of shafts 128, 129 bearing gears 130, 131 having eccentric weights 132, 133, similar to those previously described in Fig. 2.

The casing 123 is also provided with a self-aligning anti-friction thrust bearing 134 consisting of 10 the outer race 135, balls 136 and the inner race 137 disposed in a socket 138. A similar bearing 139 is located at the other end of the casing 123 for rotatably supporting the worm sleeve 140 which is provided with a worm 141 for engaging 15 teeth on the worm gears 130, 131. Sleeve 140 may be provided with annular shoulders 142, 143 for engaging the bearings 134, 139 and preventing 20 axial movement of the sleeve and the sleeve is provided with a circular bore 144 for slidably receiving the shaft 145 of motor armature 146. The bearing 139 may be secured in place by a cover plate 147 having an oil seal 148 and the shaft 145 is preferably provided with a keyway 25 149 for receiving the key 150 which also engages in a keyway 151 in the sleeve 140. The keyway 151 allows a sliding action of the key 150.

The upper end of shaft 145 may be engaged by a ball-bearing 152 resting in a circular socket 153 and engaged by a spring 154 which reacts against 30 a threaded cap 155. The other end of the armature shaft 145 may be rotatably supported in an anti-friction bearing 156 of the same type which is engaged by spring 157 which reacts against a threaded cap 158. Bearing 156 is adapted to slide 35 in socket 159, but it is maintained in the position shown by the action of springs 154, 157. The commutator 160 may be made of sufficient length to maintain the commutator in contact with the brushes 161, even though the armature may move 40 backward and forward slightly against the pressure of springs 154, 157.

The operation of the present vibrator, is as follows. The eccentric weights 132, 133, are so arranged with respect to each other that vibrations are produced in a vertical direction in Fig. 7, or in the direction of the axis of the shaft 145. The motor shaft is thus arranged to extend in the direction of the vibrations and the motor shaft is resiliently supported so that although the 50 vibrator and motor casing 125, and the motor field are vibrated with the form, these vibrations do not exert any particular strain upon the bearings of the motor, because the armature 146 may practically assume a position of rest in an axial 55 direction, and the shaft 145 may slide backward and forward in the sleeve 140 or rather, the sleeve may slide backward and forward on the shaft as the vibrator casing moves back and forth.

Shaft 145 slidably engages worm sleeve 140, but causes the worm sleeve to rotate and drive the gears 130, 131 in opposite directions in a manner similar to the vibrator of Fig. 2, but the motor shaft is not subjected to the lateral forces which tend to damage the motor bearings and the vibration merely results in relative sliding movement between the motor shaft and its bearings, which is resisted by the springs 154, 157.

Referring to Fig. 8, this is a fragmentary, detailed view of the vibrator casing 123 which is 70 provided with upwardly projecting lugs 162 for receiving the threaded end 163 of the stub shafts 128, 129, the former of which is illustrated. Stub shaft 128 is provided with the reduced threaded portion 163 and with a head 164, and the gear 75

130 is provided with the lining of bearing metal 165.

Referring to Fig. 9, it will be observed that the direct worm drive may be replaced by a worm drive through the gears 166 and pinions 167, thereby permitting the eccentric weight 132, 133 to be driven at a greater speed, and the speed of vibration is not necessarily limited to that which can be attained by the worm drive shown 10 in Fig. 7, since it will be observed that smaller pinions may be used on shafts 128, 129, and the worm 141 need not necessarily directly engage teeth on the eccentric weight gear.

The present vibrators may be used with electric motors and gearing to produce vibrations having frequency of several thousand vibrations per minute, or less, up to 3600 vibrations per minute, which is a very common motor speed, or the vibrations may be increased by the use of a 20 faster motor or speed increasing gearing to any number of vibrations per minute, which the strength of the rotating parts permits. A practical limit is that at which the fastest rotating parts may safely be rotated, this speed of rotation being limited by the centrifugal force, and the present vibrators are capable of attaining vibrations of sufficiently high frequency to produce very beneficial results in the treatment of concrete.

30 The concrete which is utilized in the forms 24 or 114, may consist of a mixture of water, Portland cement, and aggregate consisting of relatively small pieces of stone, such as marble or granite, and the mixture may be sufficiently dry so that 35 there is practically no slump in the concrete as it is placed in a form, or upon any other support. Such a mixture may be described as dry or non-workable on account of the lack of any tendency to flow into the parts of any form, and vibrators 40 of the type illustrated may be used for vibrating the green concrete at a high frequency to cause the aggregate to fill every part of the form, remove air voids and excess water, and improve the granular structure and strength of the concrete.

45 After such concrete has been subjected to vibration during the placing of the concrete, and in many cases for a short time after the concrete has been placed, the form and molded concrete member may be subjected to a wet steam bath. After this curing, the external surface of the molded concrete member is dried, ground and polished, and the concrete members so manufactured present the appearance of native granite or marble, 50 or any of the other types of stone, depending upon the kind of aggregate used.

55 The concrete members may be made in any shape, with a minimum amount of stone work, since the concrete members may be molded as desired and a very high strength may be attained by the use of high frequency vibration for treating concrete of this kind.

High frequency vibration is preferably employed with semi-wet mixtures for producing concrete of very desirable characteristics for ordinary concrete work, and in any event, sufficient water should be provided to hydrate all of the cement.

60 It will thus be observed that I have invented an improved vibrator which is adapted to produce vibrations in a predetermined direction, and which

is adapted to permit the better control of the vibrations with respect to direction, amplitude, intensity and synchronization.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. Vibrator mechanism comprising a unitary member to be vibrated, a plurality of vibrator housings secured to such unitary member and each supporting a shaft with an eccentric weight secured thereto, said weights extending from their respective shafts in the same angular direction and said shafts being set in approximately tandem alignment with each other, flexible couplings connecting the shafts of the vibrators so that they will rotate in synchronism with each other and means for imparting rotative motion to said coupled shafts.

2. Vibrator mechanism comprising a unitary member to be vibrated, a plurality of vibrator housings secured to such unitary member and each supporting a shaft with an eccentric weight secured thereto, said weights extending from their respective shafts in the same angular direction, in combination with a motor actuated driving shaft and flexible couplings connecting the shafts of the motor and vibrators in tandem so that all 30 so connected shafts will rotate in angular unison.

3. A vibrator mechanism comprising a unitary member to be vibrated, a plurality of vibrators secured to said unitary member, each vibrator having a shaft with an eccentric weight secured thereto, said weights extending from their respective shafts in the same angular direction, and said shafts being set in approximately tandem arrangement with each other, flexible couplings connecting the shafts of the vibrators so that they will rotate in synchronism with each other, and 40 means for imparting rotative motion to the coupled shafts, comprising an electric motor resiliently mounted with respect to said unitary member, and flexible driving means connecting said motor and one of the shafts of said vibrators.

4. A vibrator mechanism comprising a unitary member to be vibrated, a plurality of vibrators secured to said unitary member, each vibrator having a shaft with an eccentric weight secured thereto, said weights extending from their respective shafts in the same angular direction, and said shafts being set in approximately tandem arrangement with each other, flexible couplings connecting the shafts of the vibrators so that they will rotate in synchronism with each other, means for imparting rotative motion to the coupled shafts, comprising an electric motor resiliently mounted with respect to said unitary member, and flexible driving means connecting said motor and one of the shafts of said vibrators, 55 said flexible driving means comprising a flexible shaft extending from the motor shaft to the said latter vibrator shaft.

WALTER H. HORSCH.
